RETURN MAILING ENVELOPE

Alexander Eisemann, Jr., Westport, Conn., assignor to Chemtrol Corporation, Stamford, Conn., a corporation of Delaware

Filed Dec. 14, 1961, Ser. No. 159,307
5 Claims. (Cl. 229—73)

This invention relates to return mailing envelopes, and more particularly to such envelopes which may be folded and sealed in either of two different optional directions, providing separate spaces respectively for forward and return addresses, one of which is exposed and the other concealed when the envelope is folded.

In many commercial activities goods are sent by a customer to a processor and returned to the customer after processing. Heretofore it has been usual for the customer to transmit the goods for processing in a container and, for convenience in returning the goods, to enclose a separate self-addressed return container or label, sometimes bearing postage. The goods are returned in a separate container. Except in situations involving large and expensive containers, no provision is made as far as I am aware for reuse of the original container. Particularly in industries such as the photo finishing industry it has heretofore been customary for photo finishers to discard the container used to send exposed film to them, and to use a new container to return developed and finished photographs to the customers.

It is an object of the present invention to provide a reusable container for small articles, such as undeveloped film and developed pictures. It is another object of the invention to provide a reusable container which will conveniently bear places for two separate addresses and postage, only one of which will be exposed when the container is closed, depending on the choice of the sender. It is another object of the invention to provide such a container which is simple and inexpensive and which will embody in one structure all of the information and postage required to transmit merchandise from a customer to a processor and back to the customer again.

According to the invention in its broader aspects, I provide an envelope for return mailing and the like comprising a rectangular bag-like structure open at the top, a pair of flaps joined one to the top edge of each side of said structure and extending substantially in register therewith, clasp means adapted to cooperate with said flaps for closing said envelope and mounted on one side of said envelope near the bottom edge thereof, a first fold across said envelope mid-way between the top and bottom edges thereof, and a second fold bent oppositely to said first fold across said envelope nearer the top edge thereof.

Other and further objects and features of the invention will become more apparent from the following description of an embodiment thereof. This description refers to the accompanying drawings, wherein:

FIG. 1 shows a plan view of one side of an envelope according to the invention:

FIG. 2 is a section along line 2—2 of FIG. 1;

FIG. 2a is a detail of FIG. 2, shown exaggerated and on an expanded scale;

FIG. 3 is a section along line 3—3 of FIG. 1;

FIG. 4 shows the envelope of FIG. 1 partially folded in one direction;

FIG. 4a illustrates schematically the disposition of parts of the envelope when completely folded according to FIG. 4;

FIG. 5 is a plan view of the side of the envelope opposite that which is shown in FIG. 1;

FIG. 6 is a section along line 6—6 of FIG. 5; and

2

FIG. 7 illustrates the envelope folded in the direction opposite that shown in FIG. 4.

Referring to the drawings, the envelope comprises a pair of rectangular panels 10 and 11, made of a flexible sheet-like material such as craft paper. The panels have similar dimensions at the sides 12, 13, the bottom 14 and the top 15 of each, and are disposed with their like edges in register. The side edges 12 of each panel are joined together with an accordion-pleated insert 16 and the side edges 13 of each panel are similarly joined together with an accordion-pleated insert 17. The bottom edges 14 of each panel are joined with a flap 18 which is an extension of one of the panels and is folded over the other as appears more clearly, for example, in FIG. 2. A clasp 19 on a base 19.5 is fastened as with a suitable glue to the bottom flap 18 near the bottom edges 14. A pair of closure flaps 20 and 21 are attached to and extend in register from the top edges 15 of the panels 10 and 11 respectively and are provided with holes 20.5 and 21.5, for cooperation with the clasp 19 in closing the envelope.

A first fold 25, shown exaggerated in FIG. 2a is provided across the envelope, in both panels 10 and 11, running completely across the envelope between the side edges 12 and 13, located approximately mid-way between the bottom and top edges 14 and 15, respectively. A second fold 26 in both panels running completely across the envelope parallel to the first fold 25 is bent in the opposite direction from the first fold 25 as is shown more clearly in FIG. 2a, and is located closer to the top edge 15 than to the bottom edge 14. A convenient distance between these two folds 25 and 26 is approximately one-half inch, in an envelope having a total length of about six inches between the bottom and top edges 14 and 15, respectively. An address region 10.5 is provided on the first panel 10 between the first fold 25 and bottom edge 14. A similar address region 11.5 is provided on the second panel 11 between the first fold 25 and the bottom edge 14.

Referring now to FIGS. 4 and 4a, the envelope may be bent around the first fold 25 to bring the bottom edge 14 and the top edge 15 of the side panels substantially into register with each other, with the clasp 19 disposed on the outer surface of the first panel 10. This will expose the address portion of the first panel 10 and will conceal the second panel 11 entirely. As is illustrated in FIG. 4a the flaps 20 and 21, which are represented by a single line in FIG. 4a, may then be folded over the bottom edge 14 of the envelope, to cooperate with the clasp 19 in closing the envelope. In the position shown in FIG. 4a the envelope is bent over the first fold 25, and the second fold 26 is stressed in the direction opposite to the direction in which it is bent.

Referring now to FIG. 7 the envelope is there shown bent around the second fold 26 so that the bottom edge 14 extends beyond the top edge 15 and the flaps 20 and 21 overlie the bottom flap 18 with the holes 20.5 and 21.5 in register with the clasp 19. In this position the first fold 25 is stressed in the direction opposite to its fold direction, and the second panel 11 is exposed, exposing its address portion 11.5 while concealing the first panel 10.

It is thus clear that the envelope of the invention is a convenient return mailing device in which it is necessary only to reverse the direction in which it is folded and to close it with the original clasp for use for returning goods to a sender.

The foregoing describes an embodiment of the invention, but it is not intended to limit the claims which follow to the details of this specific embodiment.

What is claimed is:

1. An envelope for return mailing and the like comprising a rectangular bag-like structure open at the top, a pair of flaps joined one to the top edge of each side of

said structure extending substantially in register therefrom, clasp means adapted to cooperate with said flaps for closing said envelope and mounted on one side of said envelope near the bottom edge thereof, a first fold across said envelope mid-way between the top and bottom edges thereof, and a second fold bent oppositely to said first fold across said envelope nearer the top edge thereof.

2. An envelope for return mailing and the like comprising a rectangular bag-like structure having two parallel flat sides and open at the top, a pair of flaps joined one to the top edge of each side of said structure and extending substantially in register therefrom, clasp means adapted to cooperate with said flaps for closing said envelope and mounted on one side of said envelope near the bottom edge thereof, a first fold across said flat sides of said envelope nearer the top edge thereof, first indicia providing a first address panel on one of said sides between said first fold and said bottom edge, and second indicia providing a second address panel on the other of said sides between said first fold and said bottom edge.

3. An envelope for return mailing and the like comprising a pair of rectangular panels of a flexible sheet-like material, said panels having similar side, top and bottom dimensions and being disposed with their like edges in register, means joining said panels at the respective side and bottom edges of each panel, a pair of flaps joined one to the top edge of each panel and extending substantially in register therefrom, clasp means adapted to cooperate with said flaps for closing said envelope and mounted on one of said panels near the bottom edge thereof, a first fold in said envelope crossing said panels between the respective side edges thereof and disposed approximately midway between the top and bottom edges thereof, and directed so that said envelope may be folded to bring the top and bottom edges substantially into register with each other and said flaps may be bent over said bottom edges to cooperate with said clasp means, and a second fold in said envelope crossing said panels parallel to the first fold but further removed toward said top edges and bent oppositely to said first fold so that said envelope may be folded over said second fold to bring said flaps directly into position to cooperate with said clasp means.

4. An envelope for return mailing and the like comprising a pair of rectangular panels of a flexible sheet-like material, said panels having similar side, top and bottom dimensions and being disposed with their like edges in register, means joining said panels at the respective side and bottom edges of each panel, a pair of flaps joined one

to the top edge of each panel and extending substantially in register therefrom, clasp means adapted to cooperate with said flaps for closing said envelope and mounted on one of said panels near the bottom edge thereof, a first fold in said envelope crossing said panels between the respective side edges thereof and disposed approximately midway between the top and bottom edges thereof, and directed so that said envelope may be folded to bring the top and bottom edges substantially into register with each other and said flaps may be bent over said bottom edges to cooperate with said clasp means, a second fold in said envelope crossing said panels parallel to the first fold but further removed toward said top edges and bent oppositely to said first fold so that said envelope may be folded over said second fold to bring said flaps directly into position to cooperate with said clasp means, first indicia providing a first address panel on one of said panels between said first fold and said bottom edges, and second indicia providing a second address panel on the other of said panels between said first fold and said bottom edges.

5. An envelope for return mailing and the like comprising a pair of rectangular panels of flexible sheet-like material, said panels having similar side, top and bottom dimensions and being disposed with their like edges in register, expandable means joining said panels at the respective side edges of each panel, means joining said panels at their respective bottom edges, a pair of flaps joined one to the top edge of each panel and extending substantially in register therefrom, clasp means adapted to cooperate with said flaps for closing said envelope and mounted on one of said panels near the bottom edge thereof, a first fold in said envelope crossing said panels between the respective side edges thereof and disposed approximately midway between the top and bottom edges thereof, and directed so that said envelope may be folded to bring the top and bottom edges substantially into register with each other and said flaps may be bent over said bottom edges to cooperate with said clasp means, and a second fold in said envelope crossing said panels parallel to the first fold but further removed toward said top edges and bent oppositely to said first fold so that said envelope may be folded over said second fold to bring said flaps directly into position to cooperate with said clasp means.
